SPRAY HEAD

Alfred C. Arbogast, Elkhart, Ind., assignor to
 Northern Indiana Brass Company, Elkhart,
 Ind.

Application October 26, 1936, Serial No. 107,637

3 Claims. (Cl. 299—61)

The main objects of this invention are:

First, to provide a spray or sprinkling head well adapted for use on lawn sprinkling systems which is effective in the discharge of water over a substantial area and at the same time is not likely to become clogged, and one in which the movable parts are effectively protected when in retracted position.

Second, to provide a spray head embodying these advantages which is simple in its parts and the parts easily assembled and disassembled.

Objects pertaining to details and economies of the invention will definitely appear from the description to follow. The invention is defined in the claims.

A structure which embodies the features of the invention is clearly illustrated in the accompanying drawing, in which:

Fig. 1 is a fragmentary view partially in side elevation and partially in vertical longitudinal section.

Fig. 2 is an enlarged view mainly in longitudinal section on a line corresponding to line 2—2 of Fig. 1.

Fig. 3 is a transverse section on line 3—3 of Fig. 1.

Fig. 4 is a side view of the passage member designed for imparting a spiraling or swirling movement to the water discharged against the spreader or baffle member.

In the embodiment of the invention illustrated in the accompanying drawing, 1 represents the riser of the water supply system. The body member 2 is threaded upon this riser and is provided with an internal annular flange 3 beveled on its under side to provide a beveled packing seat 4. The body member is provided with a recess 5 at its upper end having an inwardly inclined bottom or inverted conical bottom 6. Above the flange 3 the body is provided with an internal longitudinal groove 7.

The tubular nozzle member 8 is provided with an upwardly flared tip portion 9, its under surface 10 being conformed to fit and seat on the bottom 6 of the recess 5 of the body member. This tip has an upstanding annular peripheral flange 11. The nozzle has a restricted throat portion 12 at the base of its flared tip. It is also provided in the embodiment illustrated with a downwardly facing shoulder 13 against which the passage member 15 is seated. The passage member 8 is fixedly secured against the shoulder preferably being of such diameter that when it is forced into position it is retained against the shoulder. It will be noted that it is substantially

spaced from the restricted throat providing a chamber of substantial area between the throat and the passage member which substantially reduces the turbulence and results in the water being uniformly discharged from the head. 5

This passage member has a plurality of peripheral spiral grooves 16 which coact with a wall of the nozzle member in providing spiral passages through which the water is delivered, thus setting up a swirling or spiraling movement to the 10 water as it is discharged through the throat 12 of the nozzle against the under side of the inverted conical baffle 17.

The baffle member 17 is provided with a stem 18 reciprocatingly supported in the central hole 15 19 in the passage member 15. This hole is preferably conical in shape while the stem is provided with a head 20 correspondingly shaped to close the central hole when the tip member is in elevated position. The head is provided with 20 a screw stud 21 threaded into the lower end of the stem.

This provides a convenient means for assembling these parts and retaining the baffle member in position to permit it to seat in the nozzle 25 tip or to be projected into position so that the water issuing from the throat 12 impinges against the under side of its inclined or conical portion 17, as a result the water being thrown out in the form of a whirling spray. 30

The nozzle is quite effective if the means were not provided for discharging water through the throat 12 with a swirling motion, but it is more effectively distributed in a uniform manner when it is discharged with a swirling motion. 35

The movement of the nozzle is controlled by its stem 22 which is connected to the nozzle by means of the coupling member 23 threaded into the lower end of the nozzle member and into which the stem is threaded. This coupling member is provided with a lug 24 engaging the longitudinal groove 7 within the body member, thus preventing rotative movement of the coupling member and permitting the stem to be threaded into the coupling member. The coupling member is threaded into the nozzle member before it is inserted into the body member. The stem 22 is provided with a head or flange 25 at its lower end carrying the conical packing 26 coacting with the seat 4 when the nozzle is in projected position. 40

To facilitate assembling the flange of the stem 22 is notched at 27 to receive a tool. The head 20 has a notch or slot 28 to receive a tool such as a screwdriver. 50

With the parts thus arranged they are simple and economical to produce and may be very easily assembled. There is little likelihood of their clogging in use, the nozzle member seating flush within the body member and the deflector or baffle 17 seating flush within the nozzle tip.

I have illustrated and described my invention in an embodiment which I have found highly satisfactory. I have not attempted to illustrate or describe certain modifications or adaptations which I contemplate as it is believed that this disclosure will enable those skilled in the art to embody or adapt my improvements as may be desired.

Having thus described my invention what I claim as new and desire to secure by Letters Patent, is:

1. In a spray head, the combination of a tubular body member provided at the top thereof with an annular recess having an inwardly inclined bottom and with an internal annular shoulder and having a longitudinal internal groove above said shoulder, an internally shouldered tubular nozzle member provided with an upwardly flared tip portion adapted to seat in said recess in said body member and having an annular upstanding peripheral flange, the edge of which is flush with the top of the body member when the nozzle is retracted, an inverted conical baffle member provided with a stem and adapted to seat within said nozzle tip and constituting a closure therefor when seated, a tubular stem for said nozzle provided with a flange at its lower end coacting with said shoulder in said body member, and a coupling threaded into said nozzle member and into which said nozzle member stem is threaded, said coupling being provided with a lug engaging said longitudinal groove in said body member.

2. In a spray head, the combination of a tubular body member provided at the top thereof with an annular recess having an inwardly inclined bottom and with an internal annular shoulder and having a longitudinal internal groove above said shoulder, a tubular nozzle member provided with an upwardly flared tip portion adapted to seat in said recess in said body member and having an annular upstanding peripheral flange, the edge of which is flush with the top of the body member when the nozzle is retracted, an inverted conical baffle member provided with a stem and adapted to seat within said nozzle tip and constituting a closure therefor when seated, a tubular stem for said nozzle provided with a flange at its lower end coacting with said shoulder in said body member, and a coupling threaded into said nozzle member and into which said nozzle member stem is threaded, said coupling being provided with a lug engaging said longitudinal groove in said body member.

3. In a spray head, the combination with a tubular body member provided with a recess at the top having an inwardly inclined bottom, said body member having a longitudinal internal groove, of a tubular nozzle member provided with an upwardly flared tip portion adapted to seat in said recess in said body member, said nozzle member having an internal flange at the base of its conical tip portion providing a restricted throat and an internal shoulder substantially spaced from said flange, a passage member disposed within said nozzle member against said shoulder therein, said passage member having a central conical opening receiving said stem, said stem being provided with a conical head seating in said opening when the baffle member is in elevated position, a tubular stem for said nozzle provided with a flange at its lower end coacting with said shoulder in said body member, and a coupling threaded into said nozzle member and into which said nozzle member stem is threaded, said coupling being provided with a lug engaging said longitudinal groove in said body member.

ALFRED C. ARBOGAST.
